UNITED STATES PATENT OFFICE.

ALBERT DUPUIS, OF EDMONTON, ALBERTA, CANADA.

ROTARY ENGINE.

1,238,650.

Specification of Letters Patent. Patented Aug. 28, 1917.

Application filed May 25, 1915. Serial No. 30,438.

To all whom it may concern:

Be it known that I, ALBERT DUPUIS, a subject of the King of Great Britain, residing at Edmonton, in the Province of Alberta and 5 Dominion of Canada, have invented new and useful Improvements in Rotary Engines, of which the following is a specification.

This invention relates to engines of the rotary type, the object in view being to pro-

10 duce an engine of the class described embodying in connection with a suitable casing, a rotor carrying movable blades against which the motive agent acts, combined with novel and reliable means for forcing an explosive mixture during the expansion thereof from an outside combustion chamber to the combustion chamber or chambers of the engine.

A further object of the invention is to 20 provide means whereby when the pressure in the exteriorly arranged combustion chamber becomes excessive, the feed of the motive liquid or fuel thereto will be arrested or temporarily cut off until the pressure is 25 reduced in said combustion chamber.

With the above and other objects in view, the invention consists in the novel construction, combination and arrangement of parts, as herein described, illustrated and claimed.

30 In the accompanying drawings:—

Figure 1 is a side elevation of the engine showing the means for charging the expansion chamber or chambers of the engine.

Fig. 2 is a sectional view of the charging 35 mechanism.

Fig. 3 is a sectional view of the cut off valve.

Referring to the drawings 1 designates the engine casing, and 3 the engine shaft.

40 Exteriorty of the engine and preferably mounted thereon is a combustion chamber 11 from which pipes 12 lead to the several intake ports of the engine. At one end the combustion chamber 11 which is preferably

45 in the form of a hollow cylinder is provided with a pump comprising a pump barrel or cylinder 13 in which is a reciprocatory piston 14 having attached thereto a connecting rod 15 the opposite end of which is connected to a wrist pin 16 on a crank wheel 17

50 which is driven by the engine shaft 3. Within the chamber 11 is arranged a valve casing 18 containing a fuel inlet valve 19 normally held seated by means of a backing

55 spring 20 which cuts off communication between the pump cylinder 13 and the valve

casing 18, the last named casing being provided with a port 21 to allow the fuel to enter the combustion chamber 11 where it is ignited by a spark plug 22 connected with a 60 source of electrical energy 23 such as a battery or magneto, the timing of the spark being effected by providing the wheel 17 with one or more circuit breaker blocks 24 in the electric circuit. 65

25 designates a carbureter from which a feed pipe 26 extends to the pump barrel or cylinder 13 adjacent to which the pipe 26 is provided with a check valve 27 to prevent the fuel from being forced back to the carbureter by the compressing action of the piston 14. 70

In order to guard against excessive pressure in the combination chamber 11, I provide a safety device shown as comprising a 75 piston 28 held seated by means of a backing spring 29, the stem 30 of said piston being connected to one arm of a lever 31 fulcrumed intermediate its ends on a support or arm 32, the other arm of said lever being connected by means of a link 33 to the arm 34 of a cut-off valve 35, said cut-off valve being closed automatically when the pressure in the chamber 11 becomes excessive. 36 designates the fuel supply tank from which a feed 80 pipe 37 leads to the carbureter 25. 85

The operation of the mechanism is as follows. As the engine is turned over, rotary motion is imparted to the wheel 17 thereby operating the pump and drawing fuel through the pipe 26 from the carbureter to the pump cylinder in the suction stroke of the piston 14, the instroke of the piston forcing said fuel into the combustion chamber where at the proper moment it is exploded by the igniter or plug 22, the exploding charge passing through the pipe 12 to the intake ports of the engine casing where still expanding it drives the rotor in a manner well understood by those familiar with the art to which this invention appertains. The wheel 17 in rotating also produces the spark at the plug 22 at the proper intervals. When the pressure in the combustion chamber 11 becomes excessive, it acts to force the valve 28 open thereby allowing the excessive pressure to escape and in such opening movement of the valve 28, the cut-off valve 35 is closed by means of the connections above described thereby automatically preventing further feed of the fuel from the carbureter to the combustion chamber. As soon as the pres-

sure in the chamber 11 falls to a safe point, the valve 28 is closed by means of the spring 29, said spring of course being of sufficient strength to hold the valve 28 closed under 5 normal conditions.

The engine is adapted to be operated by steam, compressed air, gas, or water under pressure and when comprising the external combustion chamber, the rotor may be operated by any hydrocarbon oil such as gasolene, 10 kerosene, petroleum and the like.

What I claim is:—

The combination with an engine, of means 15 for charging the expansion chamber thereof comprising a combustion chamber located exteriorly of the body of the engine, a fuel supply device, a cut-off valve controlling the latter, a pump acting to force the fuel from said supply device to said combustion cham-

ber embodying a pump barrel opening at its 20 discharge end into the combustion chamber, a spring seated check valve located within said combustion chamber and controlling the discharge end of the pump barrel, a pump operating wheel driven by the engine shaft, 25 and a spring loaded piston associated with said combustion chamber and operating under excessive internal pressure to automatically close the cut-off valve of the fuel supply and again reopen said supply when 30 the pressure is reduced to a normal point.

In testimony whereof I affix my signature in presence of two witnesses.

ALBERT DUPUIS.
